DESIGN FOR AN ESCUTCHEON PLATE

Rufus G. Fordyce, Glencoe, Ill.

Application November 22, 1938, Serial No. 81,283

Term of patent 7 years

To all whom it may concern:

Be it known that I, Rufus G. Fordyce, a citizen of the United States of America and residing at 770 Bluff Street, Glencoe, in the county of Cook and State of Illinois, have invented a new, original, and ornamental Design for an Escutcheon Plate, of which the following is a specification, reference being had to the accompanying drawing, forming a part thereof in which:

Fig. 1 is a front view of an escutcheon plate embodying my new design.

Figs. 2 and 3 are edge views of Fig. 1.

What I claim is:

The ornamental design for an escutcheon plate, substantially as shown.

RUFUS G. FORDYCE.
